UNITED STATES PATENT OFFICE.

DAVID A. POE, OF MONTREAL, CANADA, ASSIGNOR TO MERGENTHALER LINOTYPE COMPANY, A CORPORATION OF NEW YORK.

LINOTYPE-MACHINE.

No. 829,290.

Specification of Letters Patent.

Patented Aug. 21, 1906.

Application filed March 10, 1906. Serial No. 305,276.

To all whom it may concern:

Be it known that I, DAVID A. POE, residing in the city of Montreal, in the Province of Quebec, Dominion of Canada, have invented 5 a new and useful Improvement in Linotype-Machines, of which the following is a specification.

My invention relates to linotype-machines wherein circulating matrices, composed in 10 line together with expanding wedge spacers, are presented temporarily in front of a slotted mold to form type characters in relief on a slug or linotype cast in the mold.

It relates more particularly to the machine 15 represented in Letters Patent of the United States No. 734,746, to Poe & Scharf, dated July 28, 1903, wherein the composed line of matrices is advanced in a continuous path from the movable supporting devices to a position in front of the mold and thence to the carriers, which deliver them to the distributing mechanism; and it consists in improved 20 means for confining or clamping the line of matrices endwise in front of the mold.

25 In the original machine a line was presented in front of the mold carrying rigid jaws or projections at its ends, and the advancing of the mold toward the matrices caused its jaws to embrace the line, which was thereafter expanded lengthwise between the jaws by the adjustment of the spacers or justifiers. This 30 method of confining the line is open to various objections, which I now overcome by the employment of movable jaws or clamps separate from the mold and arranged to confine the line when in the casting position, as hereinafter described.

With the exception of the parts specifically 35 described and claimed herein the machine 40 may be in all respects like that represented in the patent or of any other suitable construction. In the drawings I have shown only those parts which are directly associated with my improvements.

45 Figure 1 is a vertical cross-section through the mold, matrix-support, and clamping devices on the line 1 1, Fig. 2. Fig. 2 is a top plan view of said parts, portions being shown in section.

50 Referring to the drawings, A represents the main frame. H is the slotted mold, secured in the arm h, which is mounted to oscillate around a horizontal axis and also ar-

ranged to move in an axial direction to and from the line of matrices.

55 G is a slotted line support or yoke in which the composed line of matrices Y and wedge spacers Z is sustained in front of the mold during the casting operation. The matrix-line is moved endwise horizontally into the support G through its front end and remains in the support during the casting operation, after which it is moved horizontally out of the support at the rear end of the latter toward the distributing mechanism.

55 It will be observed as a characteristic feature of the foregoing mechanism that the matrix-line is advanced intermittently along a straight or continuous path first from the usual preliminary support into the support G through the forward end of the latter and finally out of the rear end of the support G to the lifting devices.

70 The foregoing parts may all be constructed and arranged to operate in the same or essentially the same manner as the parts indicated by like letters in the original patent, except that the mold is to be made, as shown, without the end projections or jaws to confine the matrix-line.

75 For the purpose of confining the line I now provide two clamping jaws or arms U U', which may be formed and mounted in any manner that will admit of their being advanced to embrace the matrix-line while it is 80 sustained in the support G and of their being subsequently retracted from the path of the matrices that the latter may continue their course rearward out of the support. The 85 jaws are preferably made, as shown, with arms mounted on a rock-shaft u, which is sustained in the main frame and provided with a crank-arm u', connected by links u'' with the usual mold-operating cam or other source of motion. The parts are so timed 90 that after the matrix-line has arrived at the casting position in the support G the jaws swing upward opposite the respective ends of the line and serve as abutments to limit the length of the line when it is lengthened and 95 justified by the wedge spacers, which are driven upward through the line in the usual manner. After the casting action the jaws again fall, leaving the line free to be moved endwise from the support G. As the justify- 100 ing action expands the line tightly between 105

the jaws U U', it is desirable to relieve the pressure in order to permit easy downward movement of the jaws. To this end I connect the arm U to the supporting-shaft u by 5 a spline or key u^4 , seated in a longitudinal slot u^5 in the shaft, so that the distance between the arms may be varied. Upon or 10 against the outer side of the arm U, I arrange a nut u^6 , held normally against rotation around the shaft. Within this nut I mount 15 a threaded sleeve u^7 , provided with pinions u^8 , which engage a second pinion u^9 on a shaft u^{10} , mounted in the main frame and provided with a crank-arm u^{11} , connected by 20 a link u^{12} with any suitable moving part of the machine. The parts are so timed as to turn the threaded sleeve u^7 and move the jaw U toward its companion U' after they have 25 risen to embrace the matrix-line and, on the other hand, to reverse the motion of the sleeve and separate the jaws after the casting action and immediately before the jaws are lowered from the line. By turning the nut u^6 in relation to the arm U the working distance between the two arms may be varied 30 to suit the different lengths of the line which the mold of the machine may be adapted from time to time to produce. The nut may be secured in relation to the arm U by a locking-slide u^{13} , secured by a nut u^{14} or by any other suitable means. A spring u^{15} is preferably mounted between the jaws around the shaft u to force the jaws apart when they are released. In order to give additional rigidity 35 to the jaws when in action, they may be arranged to interlock with the mold in any suitable manner.

In the drawings I have shown the mold as provided at the left end with a projection h' , 40 adapted to enter a notch in the end of the jaw. At the right end of the mold I have shown a cavity h^2 , adapted to receive a projection on the end of the jaw. By thus interlocking the jaw and the mold the separation 45 of the jaws is prevented when the line is forcibly expanded between them. As the molds are commonly constructed the right end of the slot is closed by a movable liner or plate, which may be adjusted or replaced by 50 another to vary the length of the slot and of the slugs or linotypes produced. When the length of the mold is varied, the distance between the jaws will be varied to correspond.

I believe the present to be the first instance in which the mold of a linotype-machine and the means for supporting the matrices in front of the mold have been combined with jaws or confining devices distinct from the mold and adapted to move into operative position after the matrix-line is in the casting position. I also believe the present to be the first instance in which the mold and the composed matrix-line have been combined with line-confining jaws or abutments 55 adapted to interlock with the mold.

The operation of the parts is as follows: The composed line of matrices and spacers is moved endwise in the ordinary mechanism into the support G in front of the mold. The jaws U U' ascend opposite the respective 70 ends of the line. The mold advances against the matrices and into engagement with the jaws. The support G is usually lifted slightly to aline the ears of the matrices against the under edge of the mold. The 75 spacers are driven upward through the line to effect its justification, the mouth of the pot K being closed against the back of the mold and the latter filled with molten metal from the pot, as usual. The pot and mold 80 then retreat. The jaws are retracted from the ends of the line and the line carried out to the rear end of the support G toward the distributing mechanism.

Having described my invention, what I 85 claim is—

1. In a linotype-machine, the combination of a mold, a matrix-supporting yoke located adjacent to the mold and open at both ends to permit the entrance of the matrix-line at 90 one end and its delivery at the opposite end, in combination with line-confining jaws, means for advancing the jaws into and retracting them from the path of the matrices, and means for approximating and separating 95 the jaws.
2. In a linotype-machine of the character described, a mold, a horizontally-slotted matrix-support open at the forward end to admit the line of matrices and also open at the 100 rear end to permit the escape of the matrix-line, two matrix-confining jaws, and means for advancing these jaws into the slot of the support to confine the matrices before the mold, and means for retracting the jaws beyond 105 the path of the matrices.
3. In a linotype-machine, a mold, a horizontal slotted support adapted to sustain the line of matrices and spacers in front of the mold, said support open at both ends that 110 the matrices may enter at one end and escape at the other, two matrix-confining jaws pivoted to swing into and out of the matrix-path.
4. In a linotype-machine, the combination 115 of a slotted mold and line-confining jaws arranged to interlock therewith, whereby separation of the jaws during justification of the line is prevented.
5. In a linotype-machine, the combination 120 of a mold, line-confining jaws adapted to interlock with the mold and confine the line in casting position, and means for moving the jaws to and from the mold.
6. In a linotype-machine, a mold, a support for the matrix-line adjacent thereto, a rock-shaft, and two jaws carried by said shaft and adapted to embrace and confine the matrix-line in front of the mold.
7. In a linotype-machine, in combination 130

with the mold; a matrix-support, the rock-shaft, the fixed jaw U' and movable jaw U, mounted on said shaft and arranged to confine the matrices before the mold, a spring 5 tending to separate said jaws, a screw for approximating the jaws, and automatic means for actuating the screw.

8. In a linotype-machine, the combination of a mold, means for sustaining the matrix-line in front of the mold, and two vertically-swinging jaws adapted to confine the matrix-line between them.

9. In a linotype-machine and in combination with the mold and coöperating matrices, 15 a horizontal matrix-support open at both

ends that the matrix-line may be carried therethrough, two matrix-confining jaws, and means for moving the jaws vertically into the slotted support to confine the matrices therein and for retracting them beyond 20 the path of the matrices that the latter may enter and leave the support.

In testimony whereof I hereunto set my hand, this 5th day of March, 1906, in the presence of two attesting witnesses.

DAVID A. POE.
